Patented Dec. 23, 1919.

UNITED STATES PATENT OFFICE.

BRUCE R. PURVIANCE AND SAMUEL J. PURVIANCE, OF BELLOTA, CALIFORNIA.

SCRAPER.

1,325,880.

Specification of Letters Patent. Patented Dec. 23, 1919.

Application filed March 14, 1919. Serial No. 282,573.

To all whom it may concern:

Be it known that we, BRUCE R. PURVIANCE and SAMUEL J. PURVIANCE, both citizens of the United States, residing at Bellota, in the county of San Joaquin, State of California, have invented certain new and useful Improvements in Scrapers; and we do declare the following to be a full, clear, and exact description of the same, reference 10 being had to the accompanying drawings, and to the characters of reference marked thereon, which form a part of this application.

This invention relates to improvements 15 in scrapers, particularly of a type adapted to be drawn by a tractor, but which may also be horse-drawn if desired, the principal object of the invention being to provide a scraper easily operable by one man which dumps 20 its load by raising the scraper vertically from the ground instead of inverting the scraper and thus having to lift momentarily the entire weight of the load of dirt scraped.

As a second object we have produced a 25 scraper on which the operator may ride whether the load is being scraped or dumped, instead of having to walk alongside the same, as is the case with the present form of scrapers.

30 A further object is to provide a scraper which has few wearing or movable parts and which will be inexpensive of construction and yet extremely efficient for the purpose for which it is designed.

35 These objects we accomplish by means of such structure and relative arrangement of parts as will fully appear by a perusal of the following specification and claim.

On the drawings, similar characters of 40 reference indicate corresponding parts in the several views.

Figure 1 is a top plan view of our improved scraper.

Fig. 2 is a side elevation of the same, 45 showing the raised position thereof in dotted lines.

Fig. 3 is an enlarged fragmentary section of the lower end of the scraper, taken on a line 3—3 of Fig. 1.

50 Fig. 4 is a fragmentary cross section through the dirt retainer adjacent the connection thereof with the wheel supporting shaft.

Referring now more particularly to the 55 figures of reference on the drawings, the numeral 1 represents the main frame of the

scraper, substantially V-shaped on a horizontal plane, with the apex at the forward end thereof, to the rear ends of which is secured the end plates 2 of the scraper, these 60 being wider than the frame 1, the lower one 3 of which is of comparatively heavy material and normally lies adjacent the ground and forms the scraped plate.

These end plates are substantially vertical 65 and are braced and stiffened by angle members 4, each secured to the plates 2 and 3 and to the frame 1 by a single bolt 1^a and by braces 4^a running from the frame 1 thereto. The braces 4^a are adjustable relative to the 70 frame 1 in order that the angle of the frame with the scraper proper may be lessened, in the event that a hard soil is being scraped, the bolts 1^a in that case being loosened while this adjustment is being effected. The scraping plate 3 is further stiffened by means of an angle iron 5 positioned lengthwise thereof or transversely of the scraper and secured to the members 4 under the same, the plate 3 sloping somewhat from its upper to its 75 lower edge toward the front end of the scraper.

Side plates 6 are secured to the end plates and are suitably braced from the frame 1 by straps or similar means as shown at 7. 80

Positioned on top of the members 4 are bearings 8 in which are turnably mounted a shaft 9 whose ends turn down normally at a slant at each end parallel to and adjacent the side plates 6 to form arms as at 85 10, and just beyond end bearings or guides 10^a secured to the plates 2, which arms have spindles 11 projecting therefrom on which are turnably mounted supporting wheels 12.

Projecting outwardly from the shaft 9 90 is a lever arm 13, the upper end of which is pivoted to one end of a bar 14, which run forward to a lever arm 15 connected to a hand lever 16 positioned on a platform 17 secured to the frame 1, on which platform and adjacent the lever is also a ratchet quadrant 18, the lever being held in any desired position on the quadrant by means of a pawl 19 thereon adapted to mesh with the ratchets of the quadrant 18. 95

At the forward end or apex of the frame 1 is a draw bar 20 adapted to be connected to the draw bar of a tractor 21 to pull the scraper 1 and which holds the front end up.

Should it be desired to use draft animals 110 to pull the scraper, a tiller wheel is preferably positioned under the front end of the

frame 1, and the animals connected to the drawbar 20.

The operation of the device is as follows:—

5 Supposing it is desired to scrape a load, the lever 16 is positioned as shown in Fig. 2, in which position the scraping plate 3 is adjacent the ground. When it is desired to dump the dirt 22 scraped up, the lever 10 16 is pulled by the operator, who stands and rides on the platform 17.

This pulling of the lever operates to raise the scraper and frame thereof about the wheel spindles 11 as a fulcrum, the entire 15 scraper frame raising by reason of the lifting lever action of the relative positions of the main shaft 9 and the spindle 11, such raising taking place with the drawbar 20 a fixed or pivotal point in the vertical plane 20 of movement.

While the wheels 12 in the dotted raised position in Fig. 2 are shown back of their original position, this action will not be had in practice, as the tractor or team pulling the scraper constantly forward, will counteract this condition, and actually the wheels 12 will merely remain stationary for the fraction of time necessary to raise the scraper to the dumping position.

25 30 It will thus be evident that the scraper having no bottom to hold and carry the dirt, it will not be necessary to invert the scraper as is usually the case, the amount of raise of the scraper necessary to leave

the scraped dirt behind being judged by the 35 operator, and the lever pulled accordingly.

From the foregoing description it will be readily seen that we have produced such a device as substantially fulfills the object of the invention as set forth herein. 40

While this specification sets forth in detail the present and preferred construction of the device, still in practice such deviations from such detail may be resorted to as do not form a departure from the spirit 45 of the invention, as defined by the appended claim.

Having thus described our invention, what we claim as new and useful and desire to secure by Letters Patent is: 50

A scraper comprising a bottomless dirt retainer, a frame secured to and extending forward of the retainer, bearings on top of the retainer, a shaft turnably mounted in the bearings and extending beyond the ends 55 of the retainer, arms on the shaft turning downwardly and normally at a slant to the horizon, and wheels mounted on the lower ends of the arms, the shaft being arranged to turn to alter the angular position of 60 the arms.

In testimony whereof we affix our signatures in presence of two witnesses.

BRUCE R. PURVIANCE.
SAMUEL J. PURVIANCE.
